UNITED STATES PATENT OFFICE.

FRANCIS HODGKINSON, OF EDGEWOOD PARK, PENNSYLVANIA, ASSIGNEE, BY MESNE ASSIGNMENTS, TO THE COLONIAL TRUST COMPANY, TRUSTEE, OF PITTSBURGH, PENNSYLVANIA, A CORPORATION OF PENNSYLVANIA.

FLUID-PRESSURE TURBINE.

1,158,497.

Specification of Letters Patent.

Patented Nov. 2, 1915.

Application filed September 1, 1909, Serial No. 515,555. Renewed April 23, 1914. Serial No. 833,979.

To all whom it may concern:

Be it known that I, FRANCIS HODGKINSON, a subject of the King of Great Britain and Ireland, and a resident of Edgewood Park, 5 in the county of Allegheny and State of Pennsylvania, have made a new and useful Invention in Fluid-Pressure Turbines, of which the following is a specification.

This invention relates to fluid pressure 10 motors and more particularly to means for admitting fluid pressure (hereinafter called steam) from a high pressure motor to a low pressure motor.

One of the objects of this invention is to 15 provide means whereby a governor or other load responsive device will control the admission of steam to the low pressure motor.

Another object of this invention is to provide means whereby the low pressure motor 20 will receive steam from a low pressure supply until such time as the load upon that motor becomes great enough to demand augmentation of the normal fluid supply, when additional steam will be delivered to the 25 motor from a high pressure source.

The invention is herein illustrated as being applied to a multi-stage elastic fluid turbine which receives steam from the exhaust of a high pressure engine. The valve 30 mechanism, illustrative of one embodiment of my invention, is so arranged that, when the load on the turbine is light or such that the steam delivered by the engine is in excess of the demand for steam by the turbine, a valve will be opened so as to bypass a portion of the steam from the exhaust of the engine directly to the condenser so that the engine will derive the benefit of exhausting at substantially condenser pressure. When the load on the engine is light 40 and the load on the turbine is such that it demands more steam than is supplied by the engine, live or high pressure steam is automatically delivered to a high pressure stage 45 of the turbine, the exhaust steam from the high pressure engine being delivered at the same time to a lower pressure stage of the turbine.

The valve mechanism is illustrated as controlled by a speed responsive governor, 50 which operates through a relay to impart the desired opening and closing movement to a by-pass valve, arranged to admit steam

from the engine directly into the condenser. The governor, operating through a relay, 55 also actuates a valve which admits high pressure steam to a high pressure stage of the turbine.

In the drawings:

Figure 1 is a diagrammatic view of a 60 high pressure engine and a turbine, having suitable connection for conveying the steam from one to the other and provided with a valve mechanism, constructed in accordance with my invention; and Fig. 2 is 65 an enlarged sectional view through the several valve casings and the casing of a relay.

Referring to the drawings by numerals of reference: A fluid pressure motor 5, herein shown as a reciprocating engine, receives 70 motive fluid through a pipe or passage 6 from any suitable source of supply of high pressure fluid such, for example, as a steam generator not shown. The engine exhaust communicates with an exhaust pipe or passage 7, which in turn communicates with a low pressure inlet port of a turbine 9 through a branch pipe 8. The low pressure inlet port of the turbine communicates with, and is adapted to supply motive fluid to a 80 low pressure stage of the turbine. A valve 10 is located in the branch pipe 8 and will be referred to hereinafter. By-pass piping 11 communicates with the exhaust pipe 7 and, through the exhaust manifold 12 of the turbine, with a region of low pressure or a condenser 13. The manifold 12 communicates directly with the condenser 13, which, as illustrated serves for both engine 5 and turbine 9. A relief valve 90 14 is interposed in the by-pass piping 11. A valve casing 15 is also interposed in a by-pass 11 and incloses a balanced valve 16 which is adapted to seat on a valve seat 17 provided in the casing. 95

The valve 16 is provided with a stem 18 on the upper end of which a spring seat 19 is mounted. A coiled spring 20 may surround the stem 18 and by operating between the seat 19 and a seat formed on the valve 100 casing 15, tend to open the valve 16. One end of a link 23 is pivotally secured to a bracket 24 formed on the spring seat 19 and the other end is pivotally secured to a lever 25, one end of which is pivotally 105 connected to a piston rod 26.

A piston 27 is mounted on the rod 26 and is movable in a cylinder 28 which is provided with the ports 29 and 30 at its respective ends. These ports alternately 5 come inlet and exhaust ports according to the direction of movement to be imparted to the piston 27. The piston rod 26 extends through a guide 31, above the cylinder 28, and is threaded to receive a hand 10 wheel 33.

A lever 34 is fulcrumed on the piston rod 26 and is pivotally connected at the other end to a link 35 which is actuated by a load responsive device; for example, a speed 15 governor 36 of the turbine. A valve stem 37 of a relay device is pivotally connected to an intermediate point of the lever 34 by means of an adjustable link 37¹. The stem 37 is provided with collars 38 and 39 which 20 form valves in the relay device and control the operation of the piston 27. The valve 38 is adapted to close a port 40 in the casing 41 of the relay device, and the valve 39 is adapted to close a port 42, said ports being 25 supplied with liquid under pressure from some suitable source, such, for example, as an oil reservoir, through a port 43.

The oil upon entering through the port 43 may pass through the ports 40 and 29 30 into cylinder 28 above the piston 27 or through the ports 42 and 30 below the piston 27 and move the piston 27 in the desired direction. Exhaust ports 44 are provided in the casing 41 above and below the inlet 35 ports 43 and the valves 38 and 39 and the valve stem 37 are so arranged and the ports 40 and 42 are so located that when one of the ports 40 or 42 is in communication with the port 43 the other will communicate 40 with one or the other of the ports 44. This facilitates the movement of the piston 27 in one or the other direction.

The lever 25 is connected by means of a link 46 to a lever 47, fulcrumed on a bracket 45 48 secured to the valve casing 49. The casing 49 incloses a valve 50, which controls and delivers high pressure steam to the turbine 9 when the low pressure steam from the exhaust of the engine 5 is incapable of carrying the load on the turbine. The valve stem 51 of the valve 50 is connected to the lever 47 by means of a link 52 which is surrounded by a coil spring 53, the expansive force of which tends to close the valve 50 and 55 is greater than that of the spring 20 which surrounds the stem of the valve 16. The spring 53 has one end abutting against a disk 54 carried by the stem 51 and the other end abutting against an adjustable seat 55 mounted on a portion of the valve casing 49. The valve 50 is balanced and controls the delivery of high pressure steam through an inlet port 57 and outlet port 58. The inlet port 57 communicates with a source 60 of high pressure steam through piping 59

and the outlet port 58 communicates with the inlet port 60 of the high pressure stage of the turbine 9 through piping 61.

In the operation of the device as illustrated, it will be assumed that all the parts are at rest. Before starting the engine 5 the hand wheel 33 will be turned so as to raise the piston 27 and cause the valve 16 to be opened, the exhaust steam from the engine 5 will then pass through the by-pass 75 piping 11 and the valve casing 15 to the condenser 13. After the engine 5 is in operation, the valve 10 may be slightly opened to warm up the turbine 9 preparatory to starting it. Upon a further opening movement of the valve 10 steam may be admitted to a low pressure stage 62 of the turbine 9 but this steam will be unable to operate the turbine, inasmuch as there is no substantial differential of pressure between the pipes 7 85 and 12 with the valve 16 in the wide open position. Inasmuch as the turbine is at rest, the speed responsive device 36 is in a position corresponding to the low speed position, and the valve stem 37 and the valves 90 38 and 39 of the relay device are in their uppermost position and are admitting oil to the cylinder 28 above the piston 27 which is unable to move downwardly because it is held in its uppermost position by the hand 95 wheel 33. In order to start the turbine the hand wheel 33 may be turned to release the piston 27 and to permit it to move to such a position as to cause the partial closing of the valve 16 so that there is sufficient differential of pressure between the piping 8 and 100 exhaust of the turbine to start the turbine.

The hand wheel 33 may be then raised until the turbine is up to normal speed, when it may be further raised to an inoperative position. The valve mechanism will 105 then become entirely automatic and the valves 16 and 50 will be controlled wholly by the speed governor.

By referring to the drawings, it will be 110 seen that without the hand wheel 33 and with the turbine at rest and the collars 38 and 39 in their uppermost position, that as soon as the oil pressure is established the piston 27 will be forced downwardly, closing 115 the valve 16, then if the engine 5 were started with the valve 10 closed there would be no outlet for the exhaust steam, except through the relief valve 14. If, on the other hand, the valve 10 were open, a full charge 120 of the steam would be admitted to the turbine and the turbine might speed up too rapidly with the consequent ill effects.

When the turbine is operating at low speed the lever 34 is moved by a governor 125 36 of the turbine, through the agency of the link 35, to such a position that the valves 38 and 39 uncover the respective ports 40 and 42 of the relay device and place them in communication with the respective 130

ports 43 and 44. This admits oil pressure to the cylinder 28 above the piston 27 and exhausts the oil from below the piston. As the piston moves downwardly in response to the oil pressure, it first closes the valve 16 in the by-pass piping 11 and then, if a still further movement is imparted to the piston 27, the valve 50 is opened and admits high pressure steam through the piping 59 and 61 to the high pressure stage 63 of the turbine.

During the time that the piston 27 is moving down to close the valve 16, the link 46 acts as a fulcrum for the lever 25 because the valve 50 is seated, due to the expansive force of the spring 53 and because the expansive force of the spring 53 exceeds the expansive force of the spring 20. After the valve 16 has reached its seat the lever 25 fulcrums about the link 23 and opens the valve 50 in opposition to the expansive force of the spring 53. When the turbine has attained normal speed the governor 36 causes the valves 38 and 39 to close the respective ports 40 and 42 so that the piston 27 is locked in its lowest position by the confined oil in the cylinder 28, and the valve 50 is held open and live steam is delivered to the turbine. The valve 50 is not essential to the operation of the apparatus, but by employing it I insure the opening of the valve 16 in case of accident to the governor or to the valve operating mechanism.

If the load on the turbine now decreases the turbine will not require as much steam and consequently will speed up, and, through the agency of the governor 36, will move the valve stem 37 of the relay device to such a position that the ports 40 and 42 are respectively placed in communication with the port 43 and the exhaust port 44. Oil under pressure is then delivered to the cylinder 28 below the piston 27 and the piston moves upwardly. The initial upward movement of the piston permits the valve 50 to close so that the turbine receives exhaust steam from the engine 5 only. If after the valve 50 is closed the steam delivered to the turbine by the engine 5 is still in excess of the load demand on the turbine, the piston 27 will continue to rise until the valve 16 is unseated so as to pass some of the exhaust steam from the engine through the by-pass piping 11 into the condenser. When the turbine again encounters a heavy load, the valve 16 will be closed through the agency of the governor 36, the relay device and the piston 27 and if all the steam delivered by the engine is insufficient to drive the turbine, the valve 50 will again be opened and live steam will again be admitted to the high pressure stage 63 of the turbine. By admitting the high pressure steam to the high pressure stage 63 of the turbine, the steam is used more economically than if it were admitted, with the low pressure steam, to the low pressure stage of the turbine, for the reason that all the available expansive force of the high pressure steam is employed in driving the turbine. When it is desired to shut down the turbine without interfering with the operation of the engine 5, the hand wheel 33 is screwed down, thus raising the piston 27 regardless of the oil pressure in the cylinder 28 and opening the valve 16 so that the exhaust steam from the engine is by-passed around the turbine and is delivered to the condenser 13. The valve 10 may then be closed if desired.

In accordance with the provisions of the patent statutes, I have described the principle of operation of my invention, together with the apparatus which I now consider to represent the best embodiment thereof, but I desire to have it understood that the apparatus shown is only illustrative and that the invention can be carried out by other means.

What I claim is:

1. In combination with a multi-stage turbine, a source of high pressure steam supply communicating with a high pressure stage of said turbine, a source of low pressure steam supply communicating with a stage of lower pressure, a valve controlling the delivery of steam to the high pressure stage of the turbine, means for by-passing steam around the low pressure stage of the turbine and a load responsive device for actuating said valve and said means.

2. The combination of a high and low pressure motor, an exhaust pipe leading from the high pressure motor to a low pressure section of the low pressure motor, and a by-pass communicating with said exhaust pipe and leading around the low pressure motor to a condenser, a high pressure section in said low pressure motor, a source of high pressure steam supply communicating with the high pressure section, a valve controlling the delivery of steam to said high pressure section, a valve in said by-pass and automatic means for controlling both of said valves.

3. In a fluid pressure motor, a source of low pressure steam supply communicating with a low pressure section of said motor, a source of high pressure steam supply communicating with a high pressure section of said motor, a valve for controlling the delivery of steam from one of said sources to said motor, a by-pass valve for the other source, and a load responsive device for causing a movement of one of said valves without moving the other valve, said means being effective to impart an opening movement to the by-pass valve after the first described valve has closed.

4. In an engine, a high pressure section, a low pressure section, a valve for controlling

- the delivery of steam to one of said sections, a by-pass valve for the other section, and load responsive means for causing a closing and opening of one of said valves without moving the other valve, said means being effective to impart an opening movement to the other valve after the movement of the first described valve has closed.
5. In combination with a high pressure engine, a low pressure engine provided with a high and a low pressure section, means for delivering the exhaust fluid from said high pressure engine to the low pressure section of said low pressure engine, means for delivering high pressure fluid to the high pressure section of said low pressure engine, a condenser communicating with the low pressure section of said low pressure engine and a by-pass for by-passing the exhaust fluid from said high pressure engine around said low pressure section to said condenser.
6. In combination with a high pressure engine, a low pressure engine provided with a high and a low pressure section, means for delivering the exhaust of said high pressure engine to a low pressure section of said low pressure engine, means for delivering high pressure fluid to the high pressure section of said low pressure engine, a condenser communicating with the low pressure section of said low pressure engine, a by-pass for by-passing the exhaust from said high pressure engine around said low pressure section and speed responsive means for controlling the delivery of motive fluid to the high pressure section of said low pressure engine and for by-passing fluid around said low pressure section.
7. In combination with a high pressure engine, a turbine provided with a high pressure section and a low pressure section, means for delivering high pressure fluid to the high pressure section and exhaust fluid from said engine to the low pressure section of said turbine, a condenser communicating with said low pressure section, a by-pass around said low pressure section for delivering the exhaust fluid from said engine direct to said condenser and means, responsive to the load on the turbine, for controlling the delivery of fluid to said high pressure section and the delivery of fluid through said by-pass to said condenser.
8. In combination with a high pressure engine, a turbine provided with a high pressure section and a low pressure section, means for delivering high pressure fluid to the high pressure section and the exhaust fluid from said engine to the low pressure section of said turbine, a condenser communicating with said low pressure section, a by-pass around said low pressure section for delivering the exhaust fluid from said engine to said condenser and a governor controlled valve for controlling the delivery of

fluid to the high pressure section and through the by-pass.

9. In combination with a high pressure engine, a turbine provided with a high pressure section and a low pressure section, means for delivering high pressure fluid to the high pressure section and the exhaust fluid from said engine to the low pressure section of said turbine, a condenser communicating with said low pressure section, a by-pass around said low pressure section for delivering the fluid exhausted from said engine direct to said condenser, a valve for controlling the delivery of fluid to said turbine and governor controlled means for controlling the operation of said valve.

10. A combination of a high and a low pressure motor, an exhaust pipe leading from the high pressure motor to a low pressure section of the low pressure motor, a by-pass communicating with said exhaust pipe and leading around the low pressure motor to a condenser, a high pressure section in the low pressure motor, a source of high pressure steam supply communicating with the high pressure section, a valve controlling the delivery of steam to said high pressure section, a valve in said by-pass and automatic means for controlling both of said valves.

11. In combination with a high pressure engine, a low pressure engine provided with a high and a low pressure section, means for delivering the exhaust of said high pressure engine to a low pressure section of said low pressure engine, a passage for delivering high pressure fluid to the high pressure section of said low pressure engine, a condenser communicating with the low pressure section of said low pressure engine, a by-pass for by-passing the exhaust from said high pressure engine around said low pressure section to said condenser, valves for controlling the delivery of fluid to said low pressure engine and means responsive to the speed of the low pressure engine for actuating said valves.

12. In a fluid pressure engine, a high pressure section, a low pressure section, separate sources of fluid supply for each section, a valve for controlling the delivery of motive fluid to said high pressure section, means for delivering motive fluid from the low pressure supply to said low pressure section and means responsive to the speed of the turbine for by-passing motive fluid from said low pressure source of supply around said low pressure section.

13. In combination with a high pressure engine, a low pressure engine provided with a high pressure and a low pressure section, means for delivering fluid exhausted from said high pressure engine to the low pressure section of said low pressure engine, means for delivering high pressure fluid to

the high pressure section of said low pressure engine, a condenser communicating with the low pressure section of said low pressure engine and means for actuating said valve 5 and for by-passing fluid from said high pressure engine around said low pressure section to said condenser.

14. In combination with a high pressure engine, a low pressure engine provided with 10 a high pressure and a low pressure section, means for delivering fluid exhausted from said high pressure engine to the low pressure section of said low pressure engine, means for delivering high pressure fluid to 15 the high pressure section of said low pressure engine, a condenser communicating with the low pressure section of said low pressure engine and means for by-passing fluid discharged from said high pressure 20 engine around said low pressure section to said condenser.

15. In combination with a high pressure engine, a low pressure engine provided with a high pressure and a low pressure section, 25 means for delivering fluid exhausted from said high pressure engine to the low pressure section of said low pressure engine, means for delivering high pressure fluid to the high pressure section of said low pressure 30 engine, a condenser communicating with the low pressure section of said low pressure engine and speed responsive means for controlling the operation of said valve and for by-passing fluid discharged from 35 said high pressure engine around said low pressure section to said condenser.

16. In combination with an engine, a source of high pressure fluid supply, a source of low pressure fluid supply, means 40 for delivering separate streams of fluid to said engine from said sources of supply, a condenser and means for by-passing fluid from said low pressure source of supply around said engine to said condenser.

45. 17. In combination with an engine, a source of high pressure fluid supply, a source of low pressure fluid supply, means for delivering separate streams of fluid to said engine from said sources of supply, a condenser and speed responsive means for by-passing fluid from said low pressure 50 source of supply around said engine to said condenser.

18. In combination with a turbine having a high pressure section and a low pressure section, a source of high pressure fluid supply communicating with the high pressure section of said turbine, a source of low pressure supply communicating with the 55 low pressure section of said turbine, a condenser communicating with the turbine and the low pressure source of supply, means controlling the delivery of fluid from the high pressure source to the turbine and a valve between said low pressure source and

said condenser for controlling the delivery of motive fluid from said source directly to said condenser.

19. In combination, in a turbine, a high pressure section, a low pressure section 70 adapted to receive motive fluid therefrom, a source of high pressure motive fluid communicating with said high pressure section, a condenser, a source of low pressure fluid communicating with said low pressure section and said condenser, a valve between said source of low pressure fluid and said condenser and load responsive means for controlling the operation of said valve.

20. In combination in a turbine, a high 80 pressure section, a low pressure section adapted to receive motive fluid therefrom, a source of high pressure motive fluid communicating with said high pressure section, a condenser, a source of low pressure fluid 85 communicating with said low pressure section and said condenser, a valve between said source of low pressure fluid and said condenser, a valve between said source of high pressure fluid and said high pressure 90 section and load responsive means for controlling the operation of both of said valves.

21. In combination in a turbine, a high pressure section, a low pressure section 95 adapted to receive motive fluid therefrom, a source of high pressure motive fluid communicating with said high pressure section, a condenser, a source of low pressure fluid communicating with said low pressure section and said condenser, a valve between 100 said source of low pressure fluid and said condenser, a valve between said source of high pressure fluid and said high pressure section, and a governor driven by the turbine for opening the last mentioned valve 105 after the first mentioned valve is fully closed.

22. In combination with an engine, a source of high pressure fluid supply, a 110 source of low pressure fluid supply, means for delivering separate streams of fluid to said engine from said sources of supply, a condenser communicating with said source of low pressure fluid and a valve located 115 between the condenser and the low pressure fluid supply, responsive in operation to the load on the engine.

23. In combination with an engine, a source of supply of high pressure fluid, 120 means for delivering fluid from said source to said engine, a source of supply of low pressure fluid, a region of lower pressure, means communicating with said low pressure source of supply, said region of lower pressure and said engine for delivering a 125 separate stream of fluid from said source to said engine, and a valve between said source and said region of lower pressure and between said region of lower pressure and the low pressure inlet port of said engine.

24. In combination with an engine, a source of supply of high pressure fluid, means for delivering fluid from said source to said engine, a source of supply of low pressure fluid, a region of lower pressure, means communicating with said low pressure source of supply, said region of lower pressure and said engine for delivering a separate stream of fluid from said source to said engine, a valve between said source and said region of lower pressure and between said region of lower pressure and the low pressure inlet port of said engine, and means responsive to the load on said engine for controlling the operation of said valve.
25. In combination with an engine, a high pressure inlet port and a separate low pressure inlet port, a source of supply of high pressure fluid, a valve for controlling the delivery of fluid from said source to said high pressure inlet port of said engine, a source of supply of low pressure fluid, a region of lower pressure, means for establishing communication between said low pressure source of supply, said region of lower pressure and said low pressure inlet port of said engine, a valve between said low pressure source of supply and said region of lower pressure, and between said region of lower pressure and the low pressure inlet of said engine, and means responsive to the load on said engine for opening said first mentioned valve after the last mentioned valve is fully closed and for controlling the operation of both valves.
26. In combination with an engine having a separate high pressure inlet port and a separate low pressure inlet port, a source of supply of high pressure fluid communicating with said high pressure inlet port, a source of supply of low pressure fluid communicating with said low pressure inlet port, a condenser communicating with the discharge port of said engine, and means responsive to the load on said engine for bypassing fluid from said low pressure source around the engine to the condenser.
27. In combination with an engine having a separate high pressure inlet port and a separate low pressure inlet port, a source of supply of high pressure fluid communicating with said high pressure inlet port, a source of supply of low pressure fluid communicating with said low pressure inlet port, a condenser communicating with the discharge port of said engine, means for bypassing fluid from the low pressure source around the engine to the condenser, a valve controlling the delivery of fluid from the high pressure source to the high pressure inlet port of the engine, and a mechanism responsive to the load on the engine for controlling the operation of said means and said valve.

In testimony whereof, I have hereunto subscribed my name this 26th day of August, 1909.

FRANCIS HODGKINSON.
